ABSTRACT OF THE DISCLOSURE

Use of certain reaction products of amines and poly-epihalohydrins, salts thereof and corresponding quaternary ammonium derivatives for controlling microorganisms.

This application is a continuation of Ser. No. 513,569 filed Dec. 13, 1965, now abandoned.

This invention relates to a method for controlling microorganisms.

In accordance with this invention, it has been found that a particular class of polyamines and certain derivatives thereof are highly toxic to a very broad spectrum of microorganisms.

These new biocidal agents are essentially saturated aliphatic polyamines containing at least one ether moiety. They are characterized by having an essentially saturated aliphatic basic structure in which the linking atoms are carbon together with at least one but never a majority of linking oxy oxygen atoms. The characteristic structural moiety is an alkylene-oxy structure to which is attached at least two aminoalkyl moieties, each containing at least four carbon atoms. Preferably, the polyamine contains at least three such amino moieties. Preferably, there are more than one of the linking oxy oxygen atoms. The corresponding partial and full salts also are suitable, as are the corresponding compounds in which part to all of the aminoalkyl moieties are quaternary ammonium moieties. These new biological agents also suitably may contain middle halogen and/or a minor proportion of nonacidic (i.e., alcoholic) hydroxyl. The basic alkylene-oxy structure may also contain one or more carbonyl moieties, as part of ester structures.

For brevity, these biocides will be referred to herein-after as "polyamines," but this designation is intended to include not only the polyamines per se, but the corresponding quaternary ammonium derivatives and salts mentioned above and described in more detail herein-after.

Within this broad class there are certain subclasses that are of particular interest because of their ready availability. Since the character of the new biocidal agents will be more apparent from the manner in which they are prepared—by reacting an amine containing at least four carbon atoms with a suitable ether precursor—these subclasses of polyamine biocidal agents will be described in terms of the subclasses of suitable ether precursors, which are the following:

(A) Polypeihalohydrins, of which there are seven major genera:

(1) Epihalohydrin dimers and trimers, of the respective formulae:

2

wherein R' is hydrogen, lower alkyl, or is —CHR"X, R" is hydrogen or lower alkyl, and X is middle halogen—that is, bromine or chlorine.

The dimers and trimers of this subclass are described in U.S. Pat. 3,078,280.

(2) Alcohol (monohydric, ROH; polyhydric R(OH)_n) initiated, which may be represented by the formula:

wherein R is the residue of the alcohol, preferably lower alkyl or alkoxyalkyl (more preferably containing no more than six carbon atoms, and desirably no more than four carbon atoms) and may be substituted by (n-m) hydroxyl, and/or one or more middle halogen atoms, and R', R'' and X have the respective meanings already set out, n is an integer of at least one, m is an integer of at least one, but not exceeding n, and r is an integer which is the number of the moieties within the parentheses occurring within one of the moieties enclosed in brackets, m in number, and r may be zero. Preferably, the molecule contains at least one of the moieties within the parentheses. Where R is the residue of a monohydric alkyl alcohol, n thus is one, m is one, and r may be zero but preferably is at least one. Where it is the residue of a dihydric alkyl alcohol, n is two, m is one or two and r may be zero but preferably is at least one. Because of the reactivity of the hydroxyls of the alcohol, m ordinarily is two; in one of the two bracketed moieties, r preferably is at least one; it may be zero in the other, or it may be one or greater, r in one bracketed moiety may be the same as r in the other, or it may be different. When n is two and m is one, then R is hydroxyalkyl, since n-m=1. Where R is the residue of a trihydric alcohol, n is three, m is one, two or three, r preferably is at least one. Because of the difference in reactivity of the hydroxyls of the alcohol, depending upon their positions on the molecule, the values of m and r cannot be predicted. In the case of glycerol, the two hydroxyls bonded to primary carbon atoms ordinarily are of about the same reactivity (as in the dihydric alcohol) and are more reactive than the hydroxyl bonded to the secondary carbon atom. Consequently, when glycerol is used as the initiator, m ordinarily is greater than 2 but less than 3, part of R being hydroxalkyl (n-m=1). In either of the two bracketed moieties, in such case, r may be zero, or it may be one or greater. r in one bracketed moiety may be the same as r in the other, or it may be different. In trimethylolethane, and, pentaerythritol, the reactivity of the hydroxyls tends to be about the same, so that m ordinarily is three or four, respectively; r usually is the result of statistical distribution.

The alcohol initiator suitably can contain from one to a plurality of linking oxy oxygen linkages, as in alcohols prepared from polyalkylene oxides, or from glycols wherein one or more but less than all of the hydroxyls have been converted to alkyl ether moieties, as in the Cellosolve ethers and "Vcon" fluids. Suitable initiators of this general class are disclosed in U.S. Pat. 2,497,315 and 3,190,926. Both the monomeric precursors and the polymeric products described in the former are suitable. Also suitable are the high molecular weight polyoxyalkylene glycols commonly known as Carbowaxes. The alcohol initiator also can suitably contain halogen, as in the poly-epihalohydrins and diepoxides of U.S. Pat. 2,951,854.

Other patents which disclose suitable alcohol-initiated polyepihalohydrins are U.S. Pats. 2,581,464, 2,861,101, 2,891,073, 2,902,398 and 3,058,921, and copending application Ser. No. 381,262.

(3) Water-initiated, which may be represented by the formula:

and epoxides the polyamines of the invention have the formula:

wherein d and e are integers, and X' represents middle halogen or amino.

The polyamines prepared from the corresponding glycol-initiated compounds have the formula:

wherein R has the meaning already assigned.

Other preferred amines are those prepared from poly (1,4-dihalo-2,3-epoxybutanes) or the corresponding epoxides of U.S. Pat. 3,065,188. These polyamines are characterized by the structural moieties.

wherein X is middle halogen. These moieties will of course be joined together by the residue of the particular initiator used to prepare them.

A preferred class of polyamines consists of those in which more than half of the halogen content of the precursor polyepihalohydrin has been replaced by amino, for the polyamines have particularly high microbicidal activity. Still more preferably, essentially all of the halogen is replaced by amino, since the resulting polyamines appear to exhibit optimum biocidal activity. This is not to say that the polyamines containing substantial amounts of halogen are of less interest, however. It has been found that the halogen content has an effect on the mammalian toxicity of the polyamine. In general, mammalian toxicity appears to become less as halogen content increases while lower activity toward microorganisms also appears to be associated with higher halogen content, polyamines contemplated by the invention are so active toward microorganisms that in some cases over-all usefulness would dictate use of a polyamine less active toward microorganisms because of its greater safety, the lesser activity still being sufficient for the intended purpose.

Essentially any primary hydrocarbon amine or secondary di(hydrocarbon) amine of at least four carbon atoms is suitable as the precursor for preparation of polyamine biocides of this invention and essentially any tri-hydrocarbon tertiary amine of at least four carbon atoms or N-hydrocarbon heteroamine is suitable for preparation of poly(quaternary ammonium) biocides of this invention. The hydrocarbon moiety or moieties can be aliphatic, including cycloaliphatic, in character, or aromatic in character, or of mixed character. The aliphatic moieties can be of either straight-chain or branched-chain configuration. The aliphatic moieties can be saturated or olefinitely unsaturated, but preferably are free from acetylenic unsaturation. Suitable classes and species of amines that are suitable thus include the following: Alkyl-, dialkyl-, and trialkylamines, including n-, sec-, tert- and iso- butylamines, the isomeric pentylamines, hexylamines, octylamines, decylamines, dodecyl-

amines including the commercial C_{12} primary amines marketed commercially under the trade name Primene

81R, and the commercial long-chain (*t*- C_{18-22}) primary amines marketed under the trade name Primene JM-T. The amine suitably can be one of the secondary or tertiary amines corresponding to the foregoing primary

amines, in which each of the alkyl groups is the same, or is different—as in the cases, for example, of N-methyl-tert-octylamine [by tert-octylamine is meant the amine of the formula $(\text{CH}_3)_3\text{CCH}_2\text{C}(\text{CH}_3)_2\text{NH}_2$], N-methylbutylamine, N,N-dimethylethylamine, and the

like. Alkenylamines and di(alkenyl) amines, such as allylamine, diallylamine, triallylamine, methallylamine, crotylamine, and the like, are suitable; so are mixed alkenyl, alkylamines, such as N-propylallylamine, N-tert-octylallylamine, N-methylcrotylamine, and the like. Mono-, di-, and tri-cycloalkyl-, mono-, di-, and tri-cycloalkenyl- and mixed amines, such as cycloalkyl-alkylamines, cycloalkyl-dialkylamines and the like, are suitable, typical representative species being cyclohexylamine, N-methylcyclohexylamine, cyclopentylamine, dicyclopentylamine, cyclohexenylamine, N-ethylcyclopentylamine and N,N-dimethylcyclohexylamine. The aromatic primary amines, and di-aromatic secondary amines are suitable. Suitably, the aromatic group(s) can be substituted by alkyl. Typical species of these amines include phenylamine, diphenylamine, triphenylamine, bis-(*p*-methylphenyl) amine, 2,4-dimethylphenylamine and the like. Mixed alkyl arylamines, such as N-methylphenylamine, and N,N-dimethylphenylamine also are suitable. Another suitable class of amines are those in which one, two or three hydrocarbon groups is aralkyl, amines such as benzylamine, dibenzylamine, N-methylbenzylamine, N,N-dimethylbenzylamine, phenethylamine, alpha-methylbenzylamine, N-methyl-alpha-methylbenzylamine, N,N-dimethyl-alpha-methylbenzylamine, N-phenylbenzylamine, N-cyclohexylbenzylamine, and the like.

Heterocyclic secondary amines also are suitable, provided that they contain only one nitrogen, and carbon, in the hetero ring. The corresponding N-hydrocarbyl heterocyclic amines also are suitable, the character of the N-hydrocarbyl group being that suitable in the other amines already described. Preferably, the N-hydrocarbyl group is lower alkyl—desirably, from 1 to 5 carbon atoms. Suitable heterocyclic amines thus include, for example, pyridine, N-methylpyridine, pyrrolidine, piperidine, N-methylpiperidine, indole, isoquinoline, and the like, other suitable amines being mentioned in U.S. Pat. 2,483,749.

The new biocides result from reaction of epoxide linkages of the ether precursor with amines and/or replacement of halogen of the ether precursor by amino mo-

ieties. The amino moieties are either secondary or tertiary in character, depending upon whether the amine precursor was primary or secondary in character. In some cases, it will be found that a primary amine may react with more than one halogen, resulting in formation of cyclic tertiary amino moieties. This will be discussed in more detail hereinafter. Where a tertiary amine is the precursor, the resulting amino moiety is quaternary ammonium in character. Typical polyamines of this class are disclosed in U.S. Pat. 2,483,749. The quaternary ammonium compounds also can be prepared by reacting one of the polyamines in which all or part of the amino moieties are of tertiary character with an alkyl halide, according to conventional procedures.

Salts of these polyamines also are biocides; in general having properties similar to the corresponding amines. From the standpoint of use as biocides, the salts in some cases may be preferred to the corresponding amines, since the salts may have more useful solubility properties as regards water, organic solvents or other carriers used in the application and administration of biocides. Suitable salts include those of inorganic acids, such as the halogen acids, particularly the hydrohalic acids in particular hydrochloric acid and hydrobromic acid, sulfuric acid, phosphoric acid and boric acid. Both complete salts and partial salts are suitable. The salts of organic acids also are suitable, examples of suitable acids being the aliphatic mono- and polycarboxylic acids, the alkane mono- and dicarboxylic acids of up to ten carbon atoms being preferred, including those which are substituted—as for example, halogenated acids, hydroxy-substituted acids, and the like—alkane and aryl sulfonic acids, phosphonic acids, phosphinic acids, phosphorous acid and its partial esters and the like. Examples of specific acids include acetic acid, succinic acid, lactic acid and gluconic acid. The salts can be prepared in the conventional manner. In the case of the hydrogen halide salts, when polyamines of the invention are prepared in the manner which has been described, the immediate product of the preparation in many cases is the hydrogen halide salt—at least in part.

When an amine is reacted with one of the ether precursors, it first reacts with epoxide rings, opening the ring, the amino or quaternary ammonium group bonding to the terminal carbon atom, with hydroxyl being bonded to the immediately adjacent carbon atom. If halogen is present, the amine then reacts with the halogen. The amine first reacts with epoxide or halogen bonded to a terminal moiety, then with halogen bonded to an internal moiety. In the biocidal agents of this invention, if terminal epoxide and/or halogen is not present in the ether precursor, then at least two of the halogens on internal moieties must be replaced by amino.

Where the amine precursor is a primary amine, the resulting polyamine may be at least in part of tertiary cyclic character, the two halogens on the adjacent haloalkylene moieties reacting in part with the amino moiety. Thus, in the case of a polypihalohydrin such as polyepichlorohydrin, the reaction can proceed according to the equation:

In the case of a polyepihalohydrin such as 1,4-dichloro-2,3-epoxybutane, the reaction can proceed according to the equation:

Also, it has been found that in the case of the polyepihalohydrins, some cyclization of the amino-alcohol end groups can occur to form dioxane structures of the type:

10 The polyamines are prepared by mixing the ether precursor with an excess of the amine, heating the mixture to a moderately elevated temperature, then holding the mixture at the temperature for a sufficient period of time to effect the desired degree of reaction of the amine with epoxide and/or replacement of halogen by amino. An often convenient procedure is to supply sufficient of the amine to react with the ether precursor, plus sufficient excess to act as acceptor for hydrogen halide formed during the reaction, plus sufficient additional excess to act as solvent. In such operation, it is desirable to supply at least twice the amount of amine required theoretically by the number of atoms of halogen (and epoxy moieties, if present) with which reaction is desired. Ordinarily, it will not be found of sufficient additional advantage to employ in excess of about six times the amount of amine theoretically required, and in most cases, use of from three to five times the theoretical amount of amine will be found most desirable. It may in some cases be found desirable to supply an additional solvent. Suitable solvents are those in which the reactants have at least some solubility, and which are inert in the reaction mixture. Suitable solvents include lower alkanols, such as methyl, ethyl, n- and isopropyl, butyl and sec-butyl alcohols, lower ketones, such as acetone, methyl ethyl ketone and methyl isobutyl ketone, ethers, such as tetrahydrofuran and dioxane, nitromethane, aromatic or normally liquid aliphatic hydrocarbons, such as benzene, toluene, xylene, hexane, cyclohexane, liquid hydrocarbon fractions, and the like.

It has been found that reaction of amine with epoxide and replacement of halogen by amino in the ether precursors is readily effected at temperatures above about 120° C., with the extent of reaction and replacement being a direct function of time, the rate of replacement being a direct function of temperature. Preferably, temperatures of the order of about 140–160° C. are employed, for at these temperatures the rate of reaction is reasonably rapid, yet is not so rapid as to make difficult termination of the reaction when the desired degree of reaction has been effected. Temperatures in excess of about 200° C. are preferably avoided—to minimize undesirable side reactions, to insure that decomposition of components of the reaction mixture does not occur, and to reduce the pressure required to maintain the reactants as liquids. Temperatures of the order contemplated are above the boiling points of most amines. Since it is desirable that the reactants be in liquid phase, it consequently is usually necessary to conduct the reaction under such superatmospheric pressure as will maintain the amine, as a liquid. The pressure may be selected to permit refluxing of the amine, if desired, although this ordinarily will not be necessary. To establish a criterion for estimating the time required to effect a desired degree of replacement of halogen by amino, it has been found that essentially complete replacement is ordinarily accomplished in about 48 hours, at a reaction temperature of about 150° C.

The polyamine product is worked up conveniently in most cases by first treating the final reaction mixture with dilute aqueous caustic (sodium hydroxide is suitable) to saponify the amine from the hydrohalide, then treating the resulting mixture with a suitable solvent, such as ether, to extract and separate the polyamine from the aqueous phase. The ether phase then is dried, and the

ether stripped—for example, at 100° C. and 0.1 torr pressure—to yield the product.

The molecular weight range of the product of course depends primarily upon the molecular weight range of the ether precursor. The desired molecular weight range of the product thus can be accomplished by appropriate choice of precursor. However, it is possible to obtain a product of narrower molecular weight range by appropriate treatment of a product of broader molecular weight range—techniques such as distillation under vacuum, for

with sufficient dilute sodium hydroxide solution to spring the amine hydrochloride and the resulting mixture was extracted with ether. The ether phase was separated, dried, and the ether stripped at 100° C., 0.1 torr pressure. In some cases a solvent was used, but such as been found to be, in general, unnecessary.

A typical polymer used as diglycidyl polyepichlorohydrin prepared by water-initiated polymerization of epichlorohydrin, then epoxidizing the resulting polymer, according to U.S. Pat. 3,058,921. The polymer had the formula:

example, molecular distillation, chromatography, or treatment with selective solvents, are suitable.

The following examples set forth preparation of specific polyamine biocides of the invention:

EXAMPLE 1

In general, typical polyamines have been prepared by a standard procedure in which the amine, 200–400 percent excess, and the polymer were mixed and reacted at approximately 150° C., under moderate superatmospheric pressure to maintain as a liquid the particular amine used, for about 48 hours. The mixture then was mixed

wherein p and q are integers, $p+q=7$. It had an average molecular weight of 800, containing 32.1% by weight of chlorine. For brevity, it is referred to as polymer Q, referring to Table III.

Typical polyamines are listed in the following table, which indicates the particular amine and ether precursors, and gives any particularly pertinent data on the polyamine. The amine precursors are designated by Roman numerals (reference Table II), the ether precursors by letters (reference Table III) and the polyamines by Arabic numerals (reference Table I), for brevity.

TABLE I

Poly-amine	Polymer	Precursors	Remarks
1	A	V	Soluble in acetone. Do.
2	B	V	Soluble in ethanol.
3	C	IV	Soluble in warm ethanol or ether.
4	C	X	Soluble in acetone.
5	D	V	Do.
6	D	IX	Do.
7	E	V	Do.
8	E	V	Hydrochloride salt. Soluble in water.
9	F	XIX	Chloride.

 R=Glycerol-initiated polyepichlorohydrin, average molecular weight: 2000;
 S=Water-initiated polyepichlorohydrin, average molecular weight: 2400;
 T=Polyepichlorohydrin, average molecular weight: 800,000.

The polyamines contemplated by this invention have been found to be very toxic to a exceptionally broad spectrum of microorganisms, including Gram Positive bacteria, Gram Negative bacteria, Acid Fast bacteria,

microorganisms that have become resistant to control by biocides used heretofore. These polyamines have been found to be essentially nontoxic, dermally and orally, at 25 the biocidally effective dosage levels. They have been found to retain their activity in the presence of serum and other body fluids, and on surfaces, even though the surface is contaminated by dirt, spilled food, and the like. However, the polyamines have been found to be some-30 what phytotoxic at biocidally effective dosages, so that their utility may well be restricted to applications not involving living plants.

Judging from the evidence available regarding their physical, chemical and physiological properties, these 35 polyamines are useful as veterinary pharmaceuticals, as well as for control of microorganisms in situations not involving treatment of animals. Further, since these polyamines appear to be essentially nontoxic with respect to warm-blooded animals at dosages effective against 40 microorganisms, they can be used to preserve foods to be consumed by animals.

To demonstrate the effectiveness of these polyamines as biocides, the following examples are presented.

The general biocidal character of these polyamines—45 their spectra and levels of activity—was ascertained by invitro screening tests employing a variety of different kinds of microorganisms, and a standard concentration of test material amounting to 32 parts per million by weight of the broth medium used. In these tests all of 50 the 52 typical polyamines mentioned in Table I were biostatic or biocidal with respect to one or more of the microorganisms used.

55

EXAMPLE II

Described in more detail, the screening procedure was as follows: a one percent by weight solution of the test compound in a bland solvent (acetone, isopropyl alcohol 60 or the like) was prepared. The solution was aseptically added to a sterile broth that would support the growth of the test microorganism, to provide a concentration of 32 parts by weight of test compound per million parts by weight of broth. A general growth medium such as 65 Trypticase Soy Broth was used. The broth containing the test compound then was dispensed in 5 cubic centimeter amounts into sterile disposable tubes and the tubes were inoculated with an actively growing test organism and incubated at a suitable temperature. After a suitable 70 incubation period, usually 24 hours for bacteria and 72 hours for fungi, the absence or presence of growth of the microorganism was determined. The criterion used for growth: presence or absence of turbidity, sediment, or surface growth, or mycelial development, as determined by visual inspection by an experienced observer. 75

Following is a summary of the results of the testing of typical species of the polyamines described in Table I with respect to some, typical, microorganisms that were employed.

Algae:

A green alga of the Clorella type. A standard alga growth medium was used. It was found that No. 26 was algastatic at 1-3 p.p.m.; algacidal at 5 p.p.m.

TABLE IV.—TEST ORGANISM

Species, Type, Gram positive bacteria	Results, 32 p.p.m. concentration of test compound
<i>Staphylococcus aureus</i> , Smith strain 1	All gave control. ²
<i>Staphylococcus aureus</i> , FDA 209	All gave control.
<i>Staphylococcus aureus</i> , Page 1	Do.
<i>Diplococcus pneumoniae</i> 1	Nos. 10, 29, 30 and 52 not tested. All others gave control.
<i>Streptococcus fecalis</i>	All gave control.
<i>Bacillus subtilis</i>	Do.
<i>Listeria monocytogenes</i> 1	Do.
Gram negative bacteria	
<i>Erwinia carotovora</i> 1	Nos. 3, 5, 16, 30, 35, 36 and 52 not tested. All others gave control.
<i>Escherichia coli</i> , Strain B	All save Nos. 13, 45, and 52 gave control.
<i>Escherichia coli</i> , ATCC 9637	No. 13 not tested. All others save Nos. 6, 15, 45, 50 and 52 gave control.
<i>Salmonella typhimurium</i> 1	No. 13 not tested. All others save Nos. 6, 15, 23, 25, 27, 29, 30, 45, 50, and 52 gave control.
<i>Salmonella schottmuelleri</i> 1	Nos. 13, 30 and 52 were not tested. All others save Nos. 6, 15, 16, 23, 25, 27, 45 and 50 gave control.
<i>Salmonella pullorum</i> 1	No. 13 was not tested. All others save Nos. 23, 27, 45 and 52 gave control.
<i>Klebsiella pneumoniae</i> 1	Nos. 13, 23, 25 and 52 were not tested. All others save Nos. 6, 15, 16, 27, 30, 45 and 50 gave control.
<i>Proteus vulgaris</i> 1	Nos. 23 and 25 were not tested. Nos. 8, 36, and 51 gave control.
<i>Pseudomonas aeruginosa</i> 1	Nos. 13, 23, 25 and 52 were not tested. Nos. 3, 8, and 36 gave control.
<i>Shigella flexneri</i> 1	No. 13 not tested. All others save Nos. 45 and 52 gave control.
Acid fast bacteria	
<i>Mycobacterium avium</i> 1	All gave control.
<i>Mycobacterium smegmatis</i>	Do.
<i>Mycobacterium phlei</i>	Do.
Fungi—yeasts	
<i>Candida albicans</i> 1	Nos. 3, 5, 6, 7, 10, 11, 13, 15, 16, 25, 26, 27, 30, 49, 50 and 52 gave control.
<i>Candida mycoderma</i>	Nos. 13 and 52 not tested. Nos. 3, 6, 8, 10, 11, 16, 25, 26, 27, 29, 30, 45, 49 and 50 gave control.
<i>Saccharomyces cerevisiae</i>	Do.
Molds	
<i>Aspergillus niger</i>	Nos. 20 and 23 not tested. Nos. 3, 6, 7, 8, 10, 15, 16, 26, 29, 30, 36, 44, 49 and 52 gave control.
<i>Epidermophyton floccosum</i> 1	Nos. 3, 12, 16, 23, 25, 35, 36 and 52 not tested. Nos. 27, 29, 30, 45 and 51 gave control.
<i>Penicillium citrinum</i>	Nos. 23 and 25 not tested. Nos. 3, 7, 8, 15, 16, 26, 29, 30, 44, 49 and 52 gave control.
<i>Trichophyton mentagrophytes</i> 1	Nos. 3, 13, 16, 23, 25, 35, 26 and 52 not tested. Nos. 7, 8, 10, 20, 26, 27, 28, 29, 30, 44, 48, 49, 50 and 51 gave control.

¹ Known to be pathogenic.

² By "control" is meant that the test compound was biostatic or biocidal, i.e., no growth of the test organism occurred, under the test conditions.

The character of the biocidal activity of these polyamines is further illustrated by the results of the tests set out in the following examples, wherein Polyamine No. 26, typical of the polyamines, was further tested.

EXAMPLE III

In addition to the microorganisms listed in Example II, Polyamine No. 26 was tested and found to control the microorganisms listed in the following table, employing the procedure described in Example II, at a concentration of 32 p.p.m.

Table V

Gram positive bacteria:

18 strains or species of *Staphylococcus aureus*. Several of these strains or species were resistant to the usual antibiotics used to control *S. aureus*. 9 strains or species of *Streptococcus*, alpha-hemolytic. 3 strains or species of *Streptococcus*, beta-hemolytic. 3 strains or species of *Diplococcus pneumoniae*. 15 strains or species of *Escherichia coli*.

Gram negative bacteria:

5 strains of *Klebsiella pneumoniae*.

In each of the above cases, the strain or species was a clinical isolate from a hospital.

Fungi-molds:

Aspergillus tamarii
Chaetomium globosum
Cladosporium resinae
Fusarium moniliforme
Normodendrium sp.
Sclerotium rolfsii
Trichoderma sp.
Trichophyton tonsurans

other species of microorganisms that have been controlled by one or more of the polyamines include:

45 Gram positive—*Corynebacterium equi*, *Streptococcus pyogenes*, ATCC 10402

Gram negative—*Salmonella gallinarum*, *Salmonella choleraesius*, *Serratia marcescens*, *Pasteurella multocida*

50 Molds—*Penicillium italicum*, *Polyporus tulipiferus*

No drug resistance could be demonstrated following 20 days of continuous subculture of *Staphylococcus aureus* in the presence of a subbiocidal dosage of No. 26 in the culture medium.

EXAMPLE IV

55 No. 26 was tested against protozoans by a microscopic observation test. The protozoans used were mixed, non-differentiated ciliates, flagellates and paramecial types. They were treated with a solution of the polyamine and 60 observed. Control was determined by lack of motion, lack of cytoplasmic streaming and/or other activity. At a dosage of 10 p.p.m., No. 26 controlled the protozoans in from 1 to 4 minutes. (No. 28, the hydrochloride salt of No. 26, was even more active, controlling the protozoans 65 in 1 minute or less.)

EXAMPLE V

No. 26 was found to be effective against spores, as well as the vegetative phase of microorganisms. The A.O.A.C. 70 Sporicidal Test Method was used. The test organism was *Bacillus subtilis*, 7-day culture. It was found that at a dosage of 50 p.p.m., No. 26 controlled the spores in 9 minutes contact time, as compared to a contact time of 10 minutes for the standard sporicide, 2.5% hydrochloric acid. Further, it was found that the effectiveness of No. 26

was not affected by conducting the test in 20% horse serum.

EXAMPLE VI

The time required for disinfection of typical microorganisms by No. 26 was ascertained, the dosage being 1 part of No. 26 in 40,000 parts of the growth medium. The organisms used and the inactivation time for each microorganism are summarized in the following table.

Table VI

Organism:	Inactivation time
<i>Staphylococcus aureus</i> , FDA 209	1 minute.
<i>Streptococcus pyogenes</i>	45 seconds.
<i>Bacillus subtilis</i> , vegetative cells	Less than 15 seconds.
<i>Bacillus subtilis</i> , spores	9 minutes.
<i>Escherichia coli</i>	7 minutes.
<i>Salmonella choleraesuis</i>	9 minutes.
<i>Candida albicans</i>	3.5 minutes.

EXAMPLE VII

Tests were conducted to ascertain the influence, if any, of various body materials upon the effect of No. 26 to typical microorganisms. The body materials used were: serum (I), red blood cells (II) and milk (III) each at a concentration of 5% of the growth medium used and urine (IV) at a concentration of 10% of the medium. An initial dosage of 32 p.p.m. of No. 26 was used.

With *Staphylococcus aureus*, FDA 209, none of I, II and IV had any effect, but III required a dosage of 64 p.p.m. to give control. With *Escherichia coli*, Strain B, none of I, II and III had any effect. With *Candida albicans* and *Aspergillus niger*, II had no effect, but I and III required a dosage of 64 p.p.m. to give control. IV was not included in the tests against these latter two microorganisms. With *Klebsiella pneumoniae*, IV had no effect, I, II and III not being included in the tests against this microorganism.

EXAMPLE VIII

Use dilution studies with No. 26 were conducted according to the A.O.A.C. test method. A standard stainless steel cylinder, coated with asparagine to improve adherence by test organisms, was immersed in a culture for a specified time, then dried for a specified time, then placed in the solution of No. 26 for a specified time, then placed in a sterile tube, and incubated for a specified time, then was examined for growth of the test organism. The test organism used was *Staphylococcus aureus*, FDA 209. The results are reported as the concentration of No. 26 in the solution required to control the test organism. In Test A, the growth medium contained no added material. In the other tests, the growth medium contained 10% of an added material, indicated in the following table, which reports the results of the test.

TABLE VII

Test:	Added material	Concentration No. 26 required for control, parts/parts of solvent
A	None	1/25,000
B	Horse serum, sterile	1/25,000
C	Sheep red blood corpuscles, sterile	1/50,000
D	Split pea soup	1/1,000
E	Mashed potato	1/1,000
F	Mayonnaise	1/1,000
G	Catsup	1/1,000

EXAMPLE IX

A variation of the test procedure of Example VIII was made. In this test, the growth medium contained no added material, but other materials than the steel cylinder were used, to test the effectiveness of No. 26 on various surfaces. The following table indicates the nature of the sur-

faces involved, and the concentration of No. 26 required to control the organism in each case.

Table VIII

5	Concentration No. 26 required for control—parts/parts of solvent
Surface:	
Standard stainless steel	1/25,000
Unpainted wood	1/2500
Painted wood	1/25,000
Untreated cotton	1/5000
Untreated leather	1/10,000
Masonite	1/5000
Asphalt tile	1/2500
Rubber tile	1/1000
Porcelain tile	1/2500

EXAMPLE X

No. 26 and its salt, No. 28, were tested in various materials (10% concentration) by an agar-cup test. A measured amount of test material was placed in an agar cup, in which the organism, *S. aureus* FDA 209, had been inoculated, and the zone of inhibition of organism growth was measured. The test materials and results of the tests are set out in the following table. No. 26 was used where oil water solubility was desired.

TABLE IX

30	Zone of inhibition, millimeters
	Untreated control Treated
Test Material:	
No. 28	14
No. 28 in Cold Cream	0
No. 28 in Deodorant Cream	8
No. 28 in Toothpaste	9
No. 28 in light household oil	0
No. 26 in enamel base paint	9
No. 26 in latex base paint	13
	11

EXAMPLE XI

No. 26 also was screened in vivo tests, with the following results:

(1) Acute oral toxicity, LD₅₀ milligrams No. 26/kilogram of animal body weight:

45	LD ₅₀
Animal	
Mice	2160
Rats	1710
Calves and piglets, over 400.	

(2) Control of *Staphylococcus aureus* infection in mice:

- 100% effective against intraperitoneal infections;
- 67-73% effective against kidney infections, drug orally administered.

(3) Control of *Diplococcus pneumoniae*: 30-70% effective against intraperitoneal infections.

(4) Control of *Candida albicans* infections in mice: 35-51% effective against kidney infections, drug orally administered.

EXAMPLE XII

No. 26 was shown to control the Newcastle Disease Virus. In this test, the virus was diluted to 10⁻⁸ in sterile broth, and this dilution was then mixed with a solution of the polyamine and the mixture allowed to stand. At varying intervals of time the mixture was injected into the allantoic cavity of a 10-day chick embryo. This dilution of virus particles, without a drug, ordinarily will cause death of the embryo within 48-72 hours. The polyamine alone, at the concentration used, has no effect on the embryo. It was found that at a dosage of 50 p.p.m. No. 26 inactivated the virus following a 5-minute contact time.

The results of the tests that have been reported demonstrate the exceptionally broad activity of polyamines con-

templated in the invention, together with the low mammalian toxicity and other biological, and chemical and physical, properties that establish such polyamines as promising biocides for a wide variety of applications. A few of the applications these polyamines appear to be suitable for include use in proprietary medicines, as in antiseptic ointments, lotions, creams, sprays, tinctures and powders, in germicidal soaps and shampoos; in body deodorants, in cosmetics, hair oils, tonics and dressings, in shaving soaps; as sanitizers, disinfectants and sterilants for use in and around homes, barns, animal pens and shelters, and in hospitals and other public buildings and facilities; in waxes and polishes; as slimicides in industrial process water, such as cooling water and paper mill waters—to prevent slimes—and in controlling undesirable microorganisms in municipal drinking water and recreational water; in paints and other coatings, sealants, caulking compositions and the like, to prevent deterioration on the shelf and after applied; for preservation of textiles, both during storage and use—as in protection of clothing and other cloth articles against attack by mildew, molds and riots when used in tropical or other humid service; to prevent deterioration of plastics; to prevent deterioration of materials used in manufacture and/or preservation of electronic components—potting and insulating compositions and the like; to prevent deterioration of adhesives; to prevent attack of sulfate-reducing bacteria and microorganisms which attack metals, or which cause corrosion of metals; to prevent plugging of underground oil-bearing strata due to the action of microorganisms during secondary recovery; to prevent attack by microorganisms on petroleum hydrocarbon fuels and lubricants; for preventing attack by microorganisms on various non-living useful objects, such as pilings and other structural members of wharves, docks, bridges and the like, books and other documents, leather goods, and the like; as preservatives for animal foods. These *in vitro* tests show that the subject polyamines control a wide variety of bacteria and other kinds of microorganisms that cause disease in man and/or other animals, so that the polyamines appear to be of interest for protection of animals against a variety of different diseases, the polyamines being used either prophylactically or therapeutically. Because of their very low dermal toxicity to warm-blooded animals, the polyamines are of particular interest for controlling skin diseases, and as antiseptics.

The polyamines are applied for each of these purposes by conventional, known means for applying chemicals for those purposes. The polyamines in general are solids or moderately to quite viscous liquids at ordinary room temperatures. Some are soluble to varying degrees in organic liquids, while some are soluble to varying degrees in water. Hydrohalide salts tend to be more water-soluble, as do salts of lower alkanic acids. The polyamines can be applied neat, or they can be formulated in suitable liquid, solid or aerosol formulations, depending upon the intended use—criteria for selection of suitable carriers for a given use being well known in the appropriate art.

For application for control of microorganisms attacking nonliving material, the polyamine (or mixture of polyamines) may be used alone or in combination with other biocidal agents, such as bactericidal, fungicidal, viricidal, insecticidal and/or acaricidal agents. Wetting agents and, if necessary or desirable, stickers can be included. If the polyamine is to be employed in the form of an emulsion or suspension, for example in water, a cosolvent may be added, or there may be added an emulsifier, emulsion stabilizer or like additive to promote formation and maintain the emulsion or suspension. The formulation may be applied by spraying, dipping, drenching, or other suitable technique. The polyamines also can be formulated as dusts, utilizing as the carrier or vehicle such materials as tricalcium phosphate, precipitated chalk, bentonite, kaolin, Kieselguhr, etc. The polyamines also may be applied in the form of aerosols, the polyamine being dissolved or

dispersed in a solvent boiling below room temperature at atmospheric pressure. The polyamine can be applied as a solution in a suitable solvent, which may consist of two or more ingredients. In some cases a dosage of as little as 0.1 part per million of the polyamine in the formulation, thoroughly and uniformly applied to the object to be protected, may be sufficient to control the microorganism in question; however, in most cases, the polyamine dosage probably will be of the order of one part per million or greater. Usually a dosage of 100 parts per million will be sufficient for control of the microorganism. This is not to say, however, that dosages above that level—for example, dosages of the order of 500–1000 parts per million, may not be desirable in some cases simply to insure control. Concentrate formulations may contain much more of the polyamine—up to 90–95 percent, for example. Of course, in some cases, the polyamine itself may be conveniently and effectively used. U.S. Pat. 3,141,818 describes conventional practice.

The polyamines can be added to foodstuffs or containers to provide protection against attack by bacteria, yeasts, fungal molds and slime molds. As indicated by the experimental evidence, control of such microorganisms can be attained by including in the food a very small concentration of the polyamine—concentrations of the order of one or two parts per million in some cases being sufficient, with concentrations of from about 5 to about 500 parts per million by weight of the food being generally suitable, and concentrations of from about 20 to about 200 parts per million generally being optimum. In the majority of cases, a concentration greater than 1% by weight will not be required. A water solution of a water soluble polyamine or salt of a polyamine can be used, or it can be dispersed in water, or a solution of the polyamine in a suitable bland, palatable organic solvent can be used. If desired, edible emulsifying agents can be used. The polyamine can be incorporated in such carriers as vegetable oils, fats and the like, in gelatin, pectins or the like. If desired, the polyamine can be dissolved or dispersed in water, the solution or dispersion frozen, and the frozen material used in packing the food product. Solid compositions containing the polyamine can be obtained by incorporating it with a finely divided edible solid, such as milk solids, flours and the like. Any suitable and convenient technique can be used to attain and insure the necessary intimate association of the polyamine and the food product to be protected. Thus, the polyamine can be incorporated into the food product, as by mixing the polyamine with the food product. For example, hamburger, sausage and other ground meat products can be readily protected in this way. Where the food product is formed, and is essentially sterile, attack by microorganisms can be inhibited by coating the surface of the food product. To effect this coating, the food product can be dipped in a liquid or semiliquid composition of the polyamine, or washed or sprayed or painted with such a liquid or semiliquid composition, or it can be dusted with a solid composition containing the polyamine. The polyamine can be incorporated in or on materials used for wrapping the food products—paper, parchment, cloth or other porous materials used for wrapping or gelatinous materials used for coating the food products can be impregnated with the polyamine, and foil or plastic film and other non-porous wrapping materials can be coated with a polyamine. Conventional practice is illustrated in U.S. Pat. 3,044,884.

The polyamines can be used to control noxious microorganisms—for example, slime-forming microorganisms—in water, again by conventional techniques, which are illustrated in U.S. Pat. 3,006,807. The polyamines can be used to control sulfur bacteria, iron bacteria and bacteria which cause corrosion of metals by conventional techniques, which are illustrated in U.S. Pats 3,141,818, 3,089,847, and U.S. 2,987,475. These patents also illustrate conventional techniques for applying chemicals to water used in secondary oil recovery from oil wells, to

prevent plugging of oil-bearing strata as does U.S. Pat. 3,049,492; the polyamines also can be used for such purpose, by such techniques.

In general, it is necessary only to introduce one or more

in excess of the amount theoretically required to replace the halogen and epoxy moieties, if present in the polyepihalohydrin, said heating being continued to form a product having the formula

of the polyamines into the water to be treated, to provide the biocidally effective dosage. In some cases, this dosage will be as little as 0.5 part per million parts by weight of the water to be treated, while in other cases a dosage of as much as 250 parts per million may be required. Generally, the effective dosage will be found to lie within the range of from about 5 to about 100 parts per million.

The polyamines can be used in the treatment of warm-blooded animals, such as livestock and other domestic animals. The polyamines can be administered by conventional techniques, the polyamine being used neat or formulated by conventional techniques in suitable formulations conventionally employed for treating the particular animal for the particular disease. Compositions suitable for treatment of animals include in addition to the polyamine pharmaceutical or veterinary carriers which may either be solid or liquid materials. Preparations can be liquids or solids or any combination of these forms, such as syrups, elixirs, emulsions, ointments, lotions, creams, sprays, tinctures, powders, capsules or tablets, or they can be incorporated in germicidal soaps, or other preparations.

The polyamine suitably, for example, can be mixed into the feed of animals or given in their drinking water. As little as 0.1 milligram per kilogram of body weight may be sufficient or as much as 100 milligrams per kilogram of body weight may be employed. As feed or water additives a dosage of as low as 0.5 part per million or as high as 500 parts per million of the compound may be required.

Compositions of compounds of this invention and suitable inert carriers, vehicles, or diluents may contain as little as 0.0001% of the active ingredient or as much as 100% of the active compound.

We claim as our invention:

1. A method of controlling microorganisms selected from the group consisting of bacteria, fungi, algae, protozoans and spores comprising contacting said micro-

or acid salts thereof where in the amino moiety is selected from the group consisting of a secondary hydrocarbon substituted amine and a tertiary dihydrocarbon substituted amine each hydrocarbon having from 1 to 22 carbon atoms with the proviso that each amino moiety must contain at least 4 carbon atoms and be free of acetylenic unsaturation; X^1 is selected from the group consisting of amino, chloro and bromo and d and e are integers such that the average molecular weight of the polyhalohydrin starting material is from about 130 to about 1,000,000.

2. The method according to claim 1 wherein X^1 and amino are both $-\text{NH}(\text{tert-octyl})$.

3. The method according to claim 2 wherein the polyepihalohydrin is polyepichlorohydrin diepoxide having an average molecular weight of about 800.

4. The method according to claim 3 wherein the microorganisms are controlled by administering said reaction product or acid salt thereof orally or dermally to a warm-blooded animal.

5. A method of controlling microorganisms selected from the group consisting of bacteria, fungi, algae, protozoans and spores comprising contacting said microorganisms with a biocidally effective quantity of the product formed by reacting:

(a) a member selected from the group consisting of a primary hydrocarbon substituted amine and a secondary dihydrocarbon substituted amine; with

(b) a polyepihalohydrin selected from the group consisting of a polyol initiated polyepichlorohydrin, polyol initiated polyepibromohydrin, polyol initiated polyepichlorohydrin epoxide and polyol initiated polyepibromohydrin epoxide,

said reaction being effected by heating at a temperature of from about 120° C. to about 200° C. a mixture of the polyepihalohydrin and the amine, the amine being present in excess of the amount theoretically required to replace the halogen and epoxy moieties if present in the polyepihalohydrin, said heating being continued to form a product having the formula

organisms with a biocidally effective quantity of the product formed by reacting:

- (a) a member selected from the group consisting of a primary hydrocarbon substituted amine and a secondary dihydrocarbon substituted amine, with
- (b) a polyepihalohydrin selected from the group consisting of a water initiated polyepichlorohydrin, water initiated polyepibromohydrin, water initiated polyepibromohydrin, water initiated polyepichlorohydrin epoxide and water initiated polyepibromohydrin epoxide,

said reaction being effected by heating at a temperature of from about 120° C. to about 200° C. a mixture of the polyepihalohydrin and the amine, the amine being present

or acid salts thereof wherein the amino moiety is selected from the group consisting of a secondary hydrocarbon substituted amine and a tertiary dihydrocarbon substituted amine each hydrocarbon having from 1 to 22 carbon atoms with the proviso that each amino moiety must contain at least 4 carbon atoms and be free of acetylenic unsaturation, R is the residue of a polyol containing no more than 6 carbon atoms, X^1 is selected from the group consisting of amino, chloro and bromo and d and e are integers such that the average molecular weight of the polyhalohydrin starting material is from about 130 to about 1,000,000.

6. A composition adapted to control microorganisms selected from the group consisting of bacteria, fungi, al-

gae, protozoans and spores which comprises 0.0001 to 95% by weight of a product formed by reacting:

- (a) a member selected from the group consisting of a primary hydrocarbon substituted amine and a secondary dihydrocarbon substituted amine; with
  - (b) a polyepihalohydrin selected from the group consisting of a water initiated polyepichlorohydrin, water initiated polyepibromohydrin, water initiated polyepichlorohydrin epoxide, water initiated polyepibromohydrin epoxide,
- 10 said reaction being effected by heating at a temperature of from about 120° C. to about 200° C., a mixture of

the polyepihalohydrin and the amine, the amine being present in excess of the amount theoretically required to replace the halogen and epoxy moieties, if present in the polyepihalohydrin, said heating being continued to form a product having the formula

25 or acid salts thereof wherein the amino moiety is selected from the group consisting of a secondary hydrocarbon substituted amine and a tertiary dihydrocarbon substituted amine each hydrocarbon having from 1 to 22 carbon atoms with the proviso that each amino moiety must con-

or acid salts thereof wherein the amino moiety is selected from the group consisting of a secondary hydrocarbon substituted amine and a tertiary dihydrocarbon substituted amine each hydrocarbon having from 1 to 22 carbon atoms with the proviso that each amino moiety must contain at least 4 carbon atoms and be free of acetylenic unsaturation, X^1 is selected from the group consisting of amino, chloro and bromo and d and e are integers such that the average molecular weight of the polyhalohydrin starting material is from about 130 to about 1,000,000 and an inert carrier.

7. The composition according to claim 6 wherein X^1 and amino are both $-\text{NH}(\text{tert-octyl})$.

8. The composition according to claim 7 wherein the polyepihalohydrin is polyepichlorohydrin diepoxide having an average molecular weight of about 800.

9. A composition adapted to control microorganisms selected from the group consisting of bacteria, fungi, algae, protozoans and spores which comprises 0.0001 to 95% by weight of a product formed by reacting:

- (a) a member selected from the group consisting of a primary hydrocarbon substituted amine and a secondary dihydrocarbon substituted amine; with

35 tain at least 4 carbon atoms and be free of acetylenic unsaturation, R is the residue of a polyol containing no more than 6 carbon atoms, X^1 is selected from the group consisting of amino, chloro and bromo and d and e are integers such that the average molecular weight of the polyhalohydrin starting material is from about 130 to about 1,000,000 and an inert carrier.
